UNITED STATES PATENT OFFICE.

LOUIS J. HINDE AND HENRY J. HINDE, OF TOLEDO, OHIO.

BOTTOM STRUCTURE FOR METALLIC PACKAGES.

1,031,264.

Specification of Letters Patent.

Patented July 2, 1912.

Application filed March 23, 1910. Serial No. 551,145.

To all whom it may concern:

Be it known that we, LOUIS J. HINDE and HENRY J. HINDE, citizens of the United States, and residents of Toledo, in the county of Lucas and State of Ohio, have invented a certain new and useful Bottom Structure for Metallic Packages; and we do hereby declare the following to be a full, clear, and exact description of the invention, such as will 10 enable others skilled in the art to which it appertains to make and use the same, reference being had to the accompanying drawings, and to the figures of reference marked thereon, which form a part of this specification.

Our invention relates to metallic packages of the class stamped from sheet-metal and adapted for the packing of paints, white lead or other materials of a heavy nature 20 and has particular reference to the bottom structures of such packages.

The object of our invention is the provision in a drawn sheet-metal package of this class of a bottom which is integral with the 25 side wall thereof and so fashioned at its outer edge as to strengthen and materially improve the package.

The invention is fully described in the following specification and a preferred embodiment of the same illustrated in the accompanying drawing which is a central vertical sectional view of the lower portion of a sheet-metal package embodying the invention.

Referring to the drawings, 1 designates the body of a sheet-metal receptacle or package having the integral bottom or end 2. This bottom is spun inwardly through and around the annular reinforcing wire or 40 member 3 and is then doubled upon itself as at 4, with such doubled portion pressed closely to the top of the ring, and convexed back through the annular portion which is beaded on the ring 3, with its convex portion approximately meeting the bottom 45 plane of the receptacle, as shown. The side of the package preferably extends down perfectly straight to the point where it begins to bend inwardly around the ring 3, thus 50 avoiding any protrusion on the exterior of the side wall and placing the ring 3 wholly within the plane of the walls to enable the edge of the doubled portion 4 to extend entirely across the top of the ring and abut, or 55 substantially abut, against the side wall. This construction permits not only a plural-

ity of receptacles to be packed more compactly side by side due to the avoiding of lateral protrusions, but also forms a very strong bottom, as the drawing of its edge 60 inwardly around and over the top of the ring 3 causes the bottom to rest on such ring, which is itself supported directly by the sides of the package, so that internal stress downwardly is transmitted directly to 65 the ring and thence to the side walls. With this construction the bottom cannot be pushed out by any force short of that needed to buckle the material to an extent sufficient to pass the bottom through the ring. 70

We wish it understood that our invention is not limited to any particular construction or arrangement of the parts except in so far as such limitations are specified in the claims.

Having thus described our invention, what 75 we claim as new and desire to secure by Letters Patent, is,

1. A cylindrical receptacle drawn from sheet-metal and having an end closure integral with its side wall and a reinforcing 80 ring disposed therein at the base of the side wall, said end closure having its end drawn inwardly through and around the ring and doubled upon itself over the top of the ring with such doubled portion pressed closely 85 to and extending approximately across the top of the ring.

2. A metallic receptacle comprising a drawn cylindrical body having an end closure integral with its side wall spun inwardly 90 through and around a wire ring and doubled upon and convexed back through the annular portion beaded on the wire ring, said doubled portion being pressed closely to and extending across the top of the wire in substantial abutment with the side wall of the receptacle and the wire ring around which the metal is spun. 95

3. In a metallic package, a cylindrical sheet-metal body, having an integral end 100 closure, an annular wire lying in the angle of the cylindrical wall of the body and the integral closure, said end closure having a marginal portion spun inward and beaded around and over the wire, and an annular 105 portion next to the marginal portion doubled on the marginal portion and flattened down and pressed on top of the marginal portion forming a bead.

4. A cylindrical receptacle drawn from 110 sheet metal and having an end closure integral with its side wall, and a reinforcing

ring disposed therein at the base of the side wall, said end closure having its outer portion drawn inwardly through and around the ring and doubled upon itself over the top of the ring, said doubled portion extending approximately across the top of the ring and into proximity to the side wall of the receptacle.

In testimony whereof we have hereunto signed our names to this specification in the presence of two subscribing witnesses.

LOUIS J. HINDE.
HENRY J. HINDE.
